(57) **CLAIM**

The ornamental design for a LED portable camping light, as shown and described.

DESCRIPTION

FIG. 1 is a top perspective view of a LED portable camping light of my new design;

FIG. 2 is a bottom perspective view thereof;

FIG. 3 is a front view thereof;

FIG. 4 is a rear view thereof;

FIG. 5 is a top view thereof;

FIG. 6 is a bottom view thereof;

FIG. 7 is a left view thereof; and,

FIG. 8 is a right view thereof.

The broken line showing is for environmental purposes only and forms no part of the claimed design.
